(57) **CLAIM**

The ornamental design for a glue gun stand, as shown and described.

DESCRIPTION

FIG. 1 is a front top left perspective view of a glue gun stand in accordance with the present invention.

FIG. 2 is a rear top right perspective view showing the glue gun stand of FIG. 1.

FIG. 3 is a rear top right perspective view showing the glue gun stand of FIG. 1.

FIG. 4 is a rear bottom right perspective view showing the glue gun stand of FIG. 1.

FIG. 5 is a front elevation view showing the glue gun stand of FIG. 1, with the rear being a mirror image thereof.

FIG. 6 is a left elevation view showing the glue gun stand of FIG. 1.

FIG. 7 is a right elevation view showing the glue gun stand of FIG. 1.

FIG. 8 is a top plan view showing the glue gun stand of FIG. 1; and,

FIG. 9 is a front top left perspective view showing the glue gun stand of FIG. 1 with a glue gun placed in the stand. The broken lines shown in the Figures depict environmental subject matter only and are not part of the claimed design.
